United States Patent

Des. 238,741

Patented Feb. 10, 1976

238,741

COOKING SURFACE OR THE LIKE

Jerry E. Wright, Corning, N.Y., assignor to Corning Glass Works

Filed Mar. 19, 1975, Ser. No. 559,790

Term of patent 14 years

Int. Cl. D7—02

U.S. Cl. D7—121

Fig. 1

Fig. 2

FIG. 1 is a top plan view of a cooking surface or the like showing my new design.

FIG. 2 is a slightly enlarged fragmental view of an ornamentation of FIG. 1.

The cooking surface is of no substantial thickness.

I claim:

The ornamental design for a cooking surface or the like, as shown.
